(57) **CLAIM**

The ornamental design for a food holder, as shown and described.

DESCRIPTION

FIG. 1 is a perspective view of a first embodiment of a food holder;

FIG. 2 is a top plan view of a first embodiment thereof;

FIG. 3 is a bottom plan view of a first embodiment thereof;

FIG. 4 is a front elevational view of a first embodiment thereof;

FIG. 5 is a rear elevational view of a first embodiment thereof;

FIG. 6 is a left side elevational view of a first embodiment thereof;

FIG. 7 is a right side elevational view of a first embodiment thereof;

FIG. 8 is a perspective view of a second embodiment thereof;

FIG. 9 is a top plan view of a second embodiment thereof;

FIG. 10 is a bottom plan view of a second embodiment thereof;

FIG. 11 is a front elevational view of a second embodiment thereof;

FIG. 12 is a rear elevational view of a second embodiment thereof;

FIG. 13 is a left side elevational view of a second embodiment thereof;

FIG. 14 is a right side elevational view of a second embodiment thereof;

FIG. 15 is a perspective view of a third embodiment thereof;

FIG. 16 is a top plan view of a third embodiment thereof;

FIG. 17 is a bottom plan view of a third embodiment thereof;

FIG. 18 is a front elevational view of a third embodiment thereof;

FIG. 19 is a rear elevational view of a third embodiment thereof;

FIG. 20 is a left side elevational view of a third embodiment thereof;

FIG. 21 is a right side elevational view of a third embodiment thereof; and,

FIG. 22 is a perspective view showing the food holder in use. The portions shown in broken lines are included for illustrative purposes only and form no part of the claimed design.

1 Claim, 10 Drawing Sheets
